SAFETY ATTACHMENT FOR LOADING APPARATUS

Joseph H. Pierce, Tulsa, Okla.

Application June 27, 1949, Serial No. 101,614

5 Claims. (Cl. 14—71)

1

This invention relates to safety attachments for loading apparatus, and more particularly to a combined gate and bridge employed to normally close an exit from a platform, and movable downwardly to provide a bridge leading from the exit to a vehicle at one side of the platform.

As a specific illustration, to aid in describing the invention I will refer to loading rack equipment for railroad tank cars which usually includes a narrow elevated platform having hand rails at opposite sides, and a suitable number of exits through which a person walks from the platform to the tank cars.

One of the objects of the invention is to produce a strong and durable combined gate and bridge adapted to occupy an approximately upright position wherein it closes an exit, and movable downwardly to form a safe bridge structure leading from the exit, thereby avoiding hazards heretofore involved in the ordinary type of simple boards generally employed to form a walk-way from such exits. A further object is to produce a combined gate and bridge including an arrangement of details providing a very high degree of strength, associated with a counter-balancing device which enables the entire structure to be easily and quickly shifted from open to closed positions and otherwise readily manipulated, regardless of the weight of the combined gate and bridge, while also providing for accurate control of the various movements with very slight effort by an unskilled workman.

Other objects are to reduce or avoid the danger of slippage on the tread surface of the movable bridge device; and to provide an efficient bumper adapted to support the outer end portion of the bridge. In using the device, the combined gate and bridge is allowed to move downwardly about the axis of a hinge until the bumper at its outer end strikes a portion of a tank car, or other object. The bumper may include rubber cushion elements tending to prevent accidental slippage at the free end of the bridge, and not likely to seriously damage paint or other surface material onto which the bridge may be lowered.

An additional object is to provide simple hand rail attachments for one or both sides of the bridge, adapted to be folded and unfolded in response to swinging movements of the combined gate and bridge.

With the foregoing and other objects in view, the invention comprises the novel combination and arrangement of specific details shown by the accompanying drawings, which illustrate a desirable form of the invention. However, it is

2

to be understood that the scope of the invention extends to variations and modifications covered by terms of the claims hereunto appended.

Fig. 1 is a diagram of a desirable condition wherein the combined gate and bridge is adjusted for a relatively large tank car, with curved arrows suggesting that the bridge may be lifted to an approximately upright position, so as to provide a closed gate.

Fig. 2 is a top or plan view, drawn to a larger scale, and partly in section, showing the combined gate and bridge in an approximately horizontal position.

Fig. 3 is a longitudinal section on the line 3—3 in Fig. 2.

Fig. 4 is an enlarged transverse section on the line 4—4 in Fig. 3 showing a swivel connection for a foldable hand rail.

Fig. 5 is an enlarged transverse section on the line 5—5 in Fig. 2, some of the parts being broken away.

As an illustration of one form of the invention, I have shown a loading rack for railroad tank cars provided with an elevated platform 3 having a hand railing 9 including vertical posts 10 at opposite sides of an exit leading to the tank cars.

The combined gate and bridge comprises an elongated guide member A movable from an approximately upright position wherein it provides a closed gate for the exit, to a variety of approximately horizontal positions wherein it forms a bridge member leading from the exit, and an extensible bridge member B slidable along said guide member to provide for selective extension of the bridge.

A very strong and durable metallic guide member A can be conveniently formed by side beams 11 integrally united by an approximately semi-circular return bend 12 at their inner ends, and connected at their outer ends by means of transverse bars 13 which may be welded or otherwise firmly secured to the side beams 11. The guide member A (Figures 2 and 3) may also include a transverse connecting bar 14 located near the return bend 12 and having its ends welded to the side beams 11. A metallic tread 15 extending across the elongated guide member A has its side edges connected to the upper edges of the side beams, while its end edges are connected to the bar 14 and the upper end bar 13, respectively. To provide a "slip proof" tread surface, and also permit drainage of water through the bridge, the tread member 15 is preferably made of expanded metal, and its edges are preferably

welded to the surrounding frame members 11, 13 and 14. The metallic tread is thus firmly united with the rigid metallic frame to produce a very strong bridge element well adapted to safely support a person walking between the elevated platform 8 and a tank car, shown by dotted lines in Fig. 1.

The side beams 11 are preferably V-shaped in cross section, as shown in Fig. 5, to provide strong and simple channels serving as guides for the extensible bridge member B, the latter having V-shaped side beams 16 slidable in the beams 11, and end members 17 and 18 connecting said side beams 16. A second expanded metal tread 19 has its side edges welded to the upper edges of the side beams 16, and its end edges likewise united with the end members 17 and 18. The metallic tread 19 is adjacent to but lower than the tread 15.

The extensible bridge member B, comprising the side beams 16 and end bars 17 and 18 surrounding the tread 19, is a unitary article slidable below the tread 15 and between the end bars 13 (Fig. 3) of the outer guide frame, so as to provide for selective elongation of the bridge. This enables the free end of the bridge to be safely positioned on tank cars of various different dimensions. To limit outward motion of the extensible bridge member, Fig. 3 shows a stop member 20 extending downwardly from the end member 17 and adapted to engage a stop bar 21 carried by the outer guide frame. The connecting bar 14 serves as a stop to limit inward movement of the extensible bridge member.

To latch the extensible bridge member in positions to which it is adjusted, I have shown a central longitudinal beam 22 (Figures 2 and 5) connecting the end bars 17 and 18, and embracing an elongated toothed bar 23. A pawl 24 is adapted to engage the teeth at the bottom of the bar 23 as shown in Figures 3 and 5, said pawl being secured to a transverse shaft 25 mounted in bearings 26 extending downwardly from the side beams 11 to receive end portions of said shaft. An operating handle 27 (Figures 2 and 5) extending from one end of the shaft 25 is movable to release the pawl 24 from the toothed bar 23, said handle being provided with a spring 28 to normally retain the pawl in contact with the row of teeth.

To illustrate a desirable pivotal mounting for the combined gate and bridge, I have shown a hinge device comprising a pair of upper and lower hinge wings 29 and 30 embracing the inner end portion of the elongated guide frame A, said wings being integrally connected together as shown in Fig. 3, and pivotally connected to an approximately horizontal hinge pintle 31 in the form of a long rod located near the bottom of the exit between the posts 10. The combined gate and bridge is movable about the horizontal axis of the pintle 31, as suggested by arrows in Fig. 1, from an approximately horizontal position wherein it forms a bridge, to an approximately upright position wherein it closes the exit between the posts 10.

A swivel member 33 in the form of a bolt extends through the embracing hinge wings 29 and 30 and also through the transverse bar 14 of the interposed guide frame, so as to pivotally connect the combined gate and bridge to the hinge wings, the axis of said swivel member 33 being approximately at a right angle to the axis of the hinge pintle 31. Otherwise stated, when the bridge occupies a horizontal position, the axis of

the swivel bolt 33 is vertical. A bridge of this kind may be accidentally left in contact with a tank car in a train which is moved while in contact with the outer end of the bridge. In this event, the bridge will merely turn about the axis of the swivel bolt 33, without imparting injurious stresses to the bridge, or the hinge device, or to any part of the loading rack structure.

The outer end portion of the bridge is provided 10 with a bumper comprising yieldable members 34 which extend downwardly to form a yieldable support for the free end of the bridge. These elements 34 may be in the form of rubber cushions which will not seriously mar the paint when the bridge is dropped onto a tank car shell. They also 15 prevent sparking at points of contact between the bridge and a tank car, and serve as friction elements tending to prevent slippage of the free end of the bridge. When the bridge is equipped 20 with an extensible section B, the bumper device is located at the outer margin of said section.

In Figures 2 and 3 I have shown a yieldable 25 spring device associated with the hinge elements to form a counterbalance. This spring device 30 preferably comprises a pair of coil springs 35 surrounding the hinge pintle, each spring having an end extension 36 contacting with the embracing hinge member 29-30, and another end extension 37 contacting with a stationary beam 38. The springs 35 are assembled under tension to 35 provide a highly desirable balance for the rather heavy combined gate and bridge, allowing the entire structure to be very easily and quickly shifted from open to closed positions, and otherwise readily manipulated to accurately control the movements in locating the free end of the bridge at selected points on the tank cars.

As a convenient means for raising and lowering 40 the combined gate and bridge on the horizontal hinge pintle 31, I have shown a flexible connecting device which may be in the form of a chain 39 extending from an anchor 40 on one of the posts 10 to an eye 41 carried by one of the side beams 11. This operating chain may also be 45 employed to limit downward movement of the bridge. A hook 42 on one of the posts 10 may be inserted into one of the links, as shown in Fig. 3, to hold the bridge in a selected position. Another hook 43 on the same post may be inserted 50 into the eye 40 to latch the gate in its closed upright position.

As an additional factor of safety, I have shown 55 how hand rails can be conveniently applied to one or both sides of the combined gate and bridge. For example, a foldable hand rail 44 is located above one side of the frame A when the latter is lowered to form a bridge, the inner end portion of said hand rail being adjacent to one side of the 60 exit from the platform 8, where the rail is pivotally supported at 45. A post 46 is pivoted at 47 (Fig. 5) to one of the side beams 11 to support the outer end portion of the hand rail 44, while a pivot 48 connects the post to said hand rail. The post 46 and hand rail 44 are thus free to fold 65 and unfold in response to pivotal movements of the hinged bridge.

When the hinged bridge is swiveled as shown 70 at 33, to provide for accidental lateral displacement of the bridge, the hand rail 44 and its post 46 should be free to swing laterally. Therefore, I have shown a suitable swivel device comprising an angle member 49 seated on a rail 9 and movable about the vertical axis of a pivot 50, the hand rail 44 being connected to said member 49

by means of the horizontal pivot 45, as shown most clearly in Fig. 4.

This swivel device comprising the angle member 49 and its pivots 45 and 50, provides for approximately universal swinging movements of the hand rail 44, allowing said hand rail to swing upwardly and downwardly about the horizontal axis of the pivot 45, as suggested by an arrow 51 in Fig. 1, while also allowing the hand rail to swing laterally about the axis of the vertical pivot 50.

I claim:

1. In an attachment for a loading apparatus having a platform provided with an exit, a hinge member adapted to extend from the lower portion of said exit, a pintle pivotally supporting the extended hinge member, the axis of said pintle being approximately horizontal and approximately parallel with the bottom of the exit, a combined gate and bridge extending from said hinge member, and a swivel pivotally connecting said combined gate and bridge to said hinge member, the axis of said swivel being at approximately a right angle to the axis of the hinge, said combined gate and bridge being movable about the axis of said pintle from an approximately upright position wherein it provides a closed gate, to an approximately horizontal position wherein it forms a bridge leading from said exit, and the axis of said swivel being approximately vertical when the combined gate and bridge occupies a horizontal position, so as to provide for accidental horizontal displacement of the bridge about the axis of said swivel, and a yieldable counterbalance device cooperating with said pintle and extended hinge member to provide a counterbalance for said combined gate and bridge.

2. In an attachment for a loading apparatus having a platform provided with an exit, a combined gate and bridge comprising an elongated guide member movable to open and close said exit, said elongated guide member being movable from an approximately upright position, wherein it provides a closed gate, to an approximately horizontal position wherein it forms a bridge member leading from said exit, said elongated guide member including an elongated guide frame provided with V-shaped metallic side beams, and a return bend integrally uniting the inner ends of said side beams, a hinge device adapted to extend from the lower portion of said exit, said hinge device comprising a pair of hinge wings embracing the inner end portion of said elongated guide frame, and a pintle to which said wings are hinged, the axis of said pintle being approximately horizontal, a swivel member pivotally connecting said embracing hinge wings to the elongated guide frame, so as to permit swinging movements of said guide frame relative to said hinge wings, the axis of said swivel member being approximately vertical when said guide frame is in a horizontal position, a tread extending across said elongated guide frame and connected to the side beams thereof, an elongated extensible frame telescoped with said guide frame to provide for selective extension of the bridge, said extensible frame having approximately V-shaped metallic side beams embraced by and slidably in the V-shaped side beams of said guide frame, and a second tread extending across said extensible frame and connected to the side beams thereof, said second tread being adjacent to but lower than the first mentioned tread when the device is employed as a bridge.

3. In an attachment for a loading apparatus having a platform provided with an exit, a combined gate and bridge comprising an elongated guide member movable to open and close said exit, said elongated guide member being movable from an approximately upright position, wherein it provides a closed gate, to an approximately horizontal position wherein it forms a bridge member leading from said exit, said elongated guide member including an elongated guide frame provided with metallic side beams, and a transverse connecting member uniting the inner ends of said side beams, a hinge device adapted to extend from the lower portion of said exit, said hinge device comprising a pair of hinge wings embracing the inner end portion of said elongated guide frame, and a pintle to which said wings are hinged, the axis of said pintle being approximately horizontal and located near the bottom of said exit, a swivel member extending through said embracing hinge wings and also through said transverse connecting member to permit swinging movements of said guide frame relative to said hinge wings, the axis of said swivel member approximately at a right angle to the axis of said hinge pintle, a metallic tread extending across said elongated guide frame and connected to the side beams thereof, an elongated extensible frame telescoped with said guide frame to provide for selective extension of the bridge, said extensible frame having metallic side beams embraced by and slidably in the side beams of said guide frame, and a second metallic tread extending across said extensible frame and connected to the side beams thereof, said second tread being adjacent to but lower than the first mentioned tread when the device is employed as a bridge, and a bumper extending downwardly from the outer end portion of said extensible frame to form a support for the extended end of the bridge.

4. In an attachment for a loading apparatus having a platform provided with an exit, a combined gate and bridge comprising an elongated guide member movable to open and close said exit, said elongated guide member being movable from an approximately upright position, wherein it provides a closed gate, to an approximately horizontal position wherein it forms a bridge member leading from said exit, said elongated guide member including an elongated guide frame provided with V-shaped metallic side beams, and a return bend integrally uniting the inner ends of said side beams, a hinge device adapted to extend from the lower portion of said exit, said hinge device comprising a pair of hinge wings embracing the inner end portion of said elongated guide frame, and a pintle to which said wings are hinged, the axis of said pintle being approximately horizontal, a swivel member pivotally connecting said embracing hinge wings to the elongated guide frame, so as to permit swinging movements of said guide frame relative to said hinge wings, the axis of said swivel member being approximately at a right angle to the axis of said hinge pintle, an expanded metal tread extending across said elongated guide frame and connected to the side beams thereof, an elongated extensible frame telescoped with said guide frame to provide for selective extension of the bridge, said extensible frame having metallic side beams embraced by and slidably in the side beams of said guide frame, and a second expanded metal tread extending across said extensible frame and connected to the side beams thereof, said second

tread being adjacent to but lower than the first mentioned tread when the device is employed as a bridge, a frictional bumper comprising rubber cushion elements extending downwardly from the outer end portion of said extensible frame to form a support for the extended end of the bridge, and a pair of counterbalance springs coiled around said hinge pintle and contacting with said extended hinge device so as to serve as a counterbalance for the combined gate and bridge.

5. In an attachment for a loading apparatus having a platform provided with an exit, a combined gate and bridge comprising an elongated guide member movable to open and close said exit, said elongated guide member being movable from an approximately upright position, wherein it provides a closed gate, to an approximately horizontal position wherein it forms a bridge member leading from said exit, a hinge member adapted to extend from the lower portion of said exit, a pintle supporting said hinge member, the axis of said pintle being approximately horizontal, a swivel pivotally connecting said hinge member to the elongated guide member, so as to permit swinging movements of said guide member relative to said hinge member, the axis of said swivel being approximately at a right angle to the axis of said hinge pintle, an elongated extensible

bridge member telescoped with said guide member to provide for selective extension of the bridge, a foldable hand rail located above one side of said elongated guide member when the latter is extended to form a bridge member, the inner end portion of said foldable hand rail being adjacent to one side of said exit, a swivel device supporting said end portion to provide for approximately universal swinging movements of said hand rail, a post pivoted to said elongated bridge member to support the outer end of said hand rail, and a pivot connecting said post to said hand rail so as to provide for folding and unfolding of the post and hand rail in response to movements of the elongated guide member about the axis of said pintle.
